US0D1076230S

(12) **United States Design Patent** (10) **Patent No.:** **US D1,076,230 S**
(45) **Date of Patent:** **** May 20, 2025**

(54) **ARTIFICIAL EYELASH EXTENSION
APPLICATOR**

(71) Applicant: **Yin Zhou**, Jiaozhou (CN)

(72) Inventor: **Yin Zhou**, Jiaozhou (CN)

(*) Notice: Patent file contains an affidavit/declaration under 37 CFR 1.130(b).

(**) Term: **15 Years**

(21) Appl. No.: **29/953,015**

(22) Filed: **Jul. 18, 2024**

(51) **LOC (15) Cl.** **28-03**

(52) **U.S. Cl.**
